UNITED STATES PATENT OFFICE.

CHARLES R. SWAIN, OF RICHMOND HILL, NEW YORK, ASSIGNOR, BY MESNE ASSIGNMENTS, TO FISHER-THREAD DRAWING MACHINE COMPANY, A CORPORATION OF WEST VIRGINIA.

THREAD-DRAWING MACHINE.

1,145,092.

Specification of Letters Patent.

Patented July 6, 1915.

Application filed February 3, 1909. Serial No. 475,765.

To all whom it may concern:

Be it known that I, CHARLES R. SWAIN, a citizen of the United States, residing in Richmond Hill, county of Queens, and State 5 of New York, have invented a new and useful Improvement in Thread-Drawing Machines, of which the following is a description.

This invention relates to mechanism for 10 drawing threads from fabric and has particular reference to means whereby the threads are effectively removed from the fabric along a given line quickly, simply and cheaply.

15 Among the objects of my invention may be noted the following: to provide a machine which is simple in form, cheap of construction, of high speed and quiet in operation, and which performs its work perfectly, 20 positively, and with great certainty and accuracy; to provide a combination of elements which, in their coöperation, produce drawn work which cannot be distinguished from hand-drawn work after the hemstitching and spoke-stitching operations have been completed on the fabric; to provide a combination of thread-deflecting, thread-cutting, feeding and presser-foot mechanisms, which, in their coöperation, handle the work 25 30 with certainty and positiveness and which obviate the necessity of guides or other special devices for guiding the work and controlling it as it passes through the machine; and to provide in the combination just mentioned certain specific features of construction 35 of the several mechanisms which co-operate to produce the functions of the machine.

With the above objects in view, and others which will be detailed during the course 40 of this description, my invention consists in the elements, features, mechanisms, and combinations of elements and mechanisms as hereinafter described and claimed.

45 In order that my invention may be clearly understood, I have provided drawings wherein:

Figure 1 is a side elevation of a machine embodying my invention; Fig. 2 is a top-plan view of the mechanism below the cloth-plate, the latter being broken away to show the parts; Fig. 3 is a plan view of the work-plate at one end of the machine showing in top-plan the presser-foot, ledger-blade and

filling plate; Fig. 4 is a section on the line 4-4 of Fig. 3 showing also the rotary cutter and a portion of the feeding mechanism below the work-plate; Fig. 5 is a view similar to Fig. 3 showing in top-plan the same parts as the latter figure, but with the presser-foot removed, and in consequence, disclosing the feed-dogs; Fig. 6 is a side elevation of the rotary cutter and its support; Fig. 7 is a longitudinal section of the presser-foot on the line 7-7 of Fig. 3; and Fig. 8 is a side elevation and cross section of the thread-deflecting blade.

Referring to the drawings, the numeral 1 indicates the bed or work-plate of the machine, which supports the top frame composed of the vertical standard 2 with the overhanging arm 3, having at its outer end the head 4, in which operate the presser-bar 5 and the thread-deflecting or drawing blade-bar 6. The overhanging arm has journaled therein the rotary driving-shaft 7, on one end of which is the drive-pulley and balance wheel 8, and on the other end of which is the actuating-crank 9, pivotally connected to one end of a link 10, which in turn is, at its other end, pivotally connected to a block 11, clamped to the blade-bar 6, which carries at its lower end the thread-drawing or thread-deflecting blade 12. This blade is formed into a sharp, penetrating point 13 and on one side is provided with a series of teeth made, see Fig. 8, so as to provide a sharp point 14, for picking up or engaging a warp or weft thread, as the case may be, from which point an oblique wall 15 ascends to junction with a vertical wall 16, thus forming a crotch 17. The points 14 are spaced apart laterally, so as to give the blade a taper on that side and to locate them so that they will engage successive, parallel threads to a width corresponding to the lateral distance between the first and last point. Each point catches one or more threads, which slide up the inclined wall 15 into the crotch 17 and are then carried down through the work-plate and drawn, thus leaving short lengths dangling or depending to be cut off, as presently described. The oblique walls 15 are not sharpened, but are rounded or dulled so as to not break or snap the threads after deflecting the same, instead of cutting said threads before deflecting. The head also supports the presser-bar 5, in the

manner usual in sewing machines, which is spring-controlled and capable of being lifted by a hand-lever in precisely the same manner as in the ordinary sewing machine, 5 and as this structure is very common it has been deemed unnecessary to illustrate the same.

The lower end of the bar 5, carries a presser-foot, see Figs. 3, 4 and 7, the shank 10 18 of which is fixed to the bar in any suitable way, said shank having the two parallel arms 19, to each of which is connected a foot or pad comprising the flat, cloth-clamping portion 20 and two, vertical, parallel bars 21, between which one of the arms 19 is inserted and to which latter the pad is loosely connected by means of pins 22, extending transversely through the arms 19 of the shank and the bars 21 of the foot, 15 20 the latter being provided with vertical, elongated slots 23 in which said pins freely play. The normal, depressed position of the pads on the shank-arms is maintained by means of a leaf-spring 24, which is curved longitudinally and set between the shank-arms 25 and the top surface of the pad 20, between the parallel bars 21 thereof. Hence, when the presser-bar is allowed to descend so as to bring the pads or feet into coöperation 30 with the feed-dogs of the feeding mechanism, said pads or feet will coöperate yieldingly with said feed-dogs in addition to, and independently of, the yielding pressure imparted to them by means of the usual coiled-spring surrounding the presser-bar having the normal tendency, as in sewing machines, 35 to force the presser-foot upon the work-plate. The special function of the inserted springs is to enable the feed to yield relatively to the presser-bar or relatively to the 40 arms of the shank, and relatively to each other, so that, when the foot is depressed against the material and the feed-dogs co-operate therewith, the clamping action of 45 the feet and feed-dogs is yielding, while there is an independent, relatively yielding movement between said feet and dogs. This is important in connection with fine fabrics, 50 such as muslins, lawns, and the very fine linens which are usually made into handkerchiefs, and in connection with varying thicknesses of work.

Viewing Fig. 3, it will be seen that the right-hand pad or foot is made with a widened inner portion 25 in the rear and a narrowed portion 26 in front, making the shoulder 27, and that the left-hand pad or foot is provided with the widened inner portion 28 in front and the narrowed portion 29 in the rear, making the opposing shoulder 30, the two shoulders being separated a short distance and leaving between them a small space 31, through which the deflecting-blade 12 reciprocates. Each pad or foot along its 65 outside is formed with the widened portion

32. By forming the pads or feet in this manner, the fabric is held flat and smooth all around the point of penetration of the blade and, as the blade goes down into the fabric, the latter is prevented from being 70 distorted, and as the blade rises from the fabric the latter is prevented from being drawn up, the adjacent portions of the two pads or feet, around the space or opening 75 31, operating as a stripper.

The work-plate has set therein two separate throat-plates 33 and 34, the inner edges of which, see Fig. 5, are separated to leave a transverse slot between the two, in which are set the filling-plate 35, and the ledger-blade 36, the latter being beveled from its top to its bottom so as to provide a cutting edge 37, and said plate and blade being arranged in alinement with their adjacent ends separated the same distance as the two shoulders of the presser-feet are separated, for the purpose of continuing said opening 31 and allowing the free reciprocation of the blade through the work-plate. Each of the throat-plates is provided with a wide outer slot 38 and a narrow inner slot 39, the several slots being arranged in parallelism and extended transversely of the said plates and of the machine. These slots receive the several portions of the feed-dogs, which operate therethrough into coöperation with the presser-feet and the intervening portions 40 of each of the throat-plates constitute a bar which supports the work and which enters the slot between the two parts of the feed-dog when the latter is projected through the throat-plates for the purpose of feeding the work as presently described. The filling-plate is made adjustable longitudinally on the work-plate by enlarging the end 41 105 thereof and longitudinally slotting the same at 42 for the passage of a clamping-screw 43, which is tapped into the work-plate, the latter being countersunk at 44 to receive said enlarged end 41 and permit it to be adjusted 110 therein, the filling-plate surface being flush with the work-plate surface. The ledger-blade 36 is arranged in the work-plate in the countersink 45, and provided with an enlarged end 46, having a slot 47, through 115 which is passed a clamping-screw 48, tapped into the work-plate, all precisely as the filling-plate. Each throat-plate 33 and 34 is provided with a solid portion 49, next to and paralleling the filling-plate and ledger-blade. By loosening the clamping-screws, the filling-plate and ledger-blade may be adjusted to proper position so as to make the opening, for the thread-drawing blade between the two, larger or smaller as the 120 case may be, or to maintain the same of a uniform width should the ledger-blade be reduced in length by sharpening the same to keep an edge thereon.

The feeding mechanism is, generally 125

speaking, of the four-motion type and comprises the rock-shaft 50, journaled at its opposite ends in brackets of the cloth-plate and provided at its forward end with the 5 two crank-arms 51 arranged in parallelism and each carrying a grooved, pivoted shoe 52, receiving a feed-bar 53, the said bars being arranged in parallelism and connected at their opposite ends to and by a pin 54 to 10 a crank-arm 55, carried by a rock-shaft 56, journaled at its opposite ends in brackets of the work-plate. Each of the feed-bars carries a dog, which is fixed thereto in any suitable way, each dog being provided with a 15 wide bar 57 and a narrow bar 58, the upper surfaces of which are serrated and which operate, respectively, through the wide and narrow slots of the throat-plates. The rock-shaft 50 is driven by the yoke 59, fixed there- 20 to between its ends and actuated by an eccentric 60, fixed upon the cutter-shaft 61, which is journaled to rotate substantially in the center of the bed of the machine in bearings 62 thereof, there being three bearings for 25 said shaft, one at the rear end, one substantially in the middle thereof and the other at the forward end. Said cutter-shaft also carries a pinion 63, fixed by its collar there- 30 to, which meshes with a gear 64, provided in its face with a cam-groove, not shown, in which runs an anti-friction roll, not shown, carried by a pin 65, set in the crank-arm 66 on one end of a short rock-shaft 67, journaled in a hanger 68, secured to the bottom 35 of the work-plate, a crank-arm 69 on the other end of said rock shaft which is grooved longitudinally for the reception of an anti-friction roll carried by a pin 70 on one end of a link 71, the other end of 40 which is pivotally connected to a crank 72, carried by the feed rock-shaft 56. This mechanism is of the usual type for imparting the longitudinal reciprocation to the feed-dogs with such variations in the length 45 of said reciprocations as may be produced by adjusting, in the ordinary manner, the pin 70 on the link 71 longitudinally of the vibratory grooved arm 69. The eccentric 60 and yoke-arm 59 give to the shaft 50 a rock- 50 ing motion, which, through the crank-arms 51, carrying the shoes 52, supporting the feed-bars 53, imparts to the latter the vertical rise and fall, thus securing the usual four motions of the now well-known four-motion 55 feed. Further details of this feed-actuating mechanism have not been illustrated, since my invention does not reside in the details of construction, but in its combination with the other coöperating elements of the 60 thread-drawing mechanism. An important feature of my invention resides in the duplex character of this feeding mechanism and the coöperating presser-foot mechanism, since, by making the feed-dogs independent 65 and the feet independent, I am enabled to obtain a relative yielding movement between the two sets of devices for the purposes previously stated; locate the dogs and feet on opposite sides of the path of reciprocation of the thread-drawing blade; separate the 70 dogs to allow space for said blade and for the rotary cutter, presently described, to operate in; provide a work-support and clamping-foot at practically every point around the thread-drawing point; and absolutely 75 insure the stripping of the work from said blade, provide a positive but yielding clamp for the work, prevent the work from being dragged through the work-plate at any point, compel the work to be fed evenly on 80 opposite sides of the thread-drawing line, and insure the production of a straight line of thread-drawing.

The cutter-shaft 61 is caused to rotate through links 73 connected thereto at their 85 lower ends and driven at their upper ends by eccentrics 74 carried by the main-shaft 7 in the usual manner. The forward end of the cutter-shaft has fixed thereto, see Figs. 2 and 6, the cutter-carrier 75 to the outer end 90 of which is pivotally connected the cutter-support 76, by means of the screw or headed pin 77, the said cutter-support being pro- 95 vided with the opposite lugs 78, through which are tapped adjusting-screws 79, be- tween the inner ends of which is arranged the extension 80 of the cutter-support 76. By manipulating these screws, the cutter- 100 support can be adjusted on the carrier to regulate the position of the cutter-blade 81 relatively to the ledger-blade 36, so that the two may have a perfect coöperation. The upper end of the cutter-support is elongated, as shown, and thereto is adjustably fixed the shank of the cutter by means of the 105 clamping-screws 82, which pass through elongated slots 83 in said shank and are tapped into the carrier.

The cutter comprises the shank and the 110 blade-portion 84, arranged at an angle thereto, the forward edge of which is inclined and beveled from its bottom to its top to provide the cutting-edge 85. A pilot or horn 86 is carried by the cutter-blade at its forward end and preferably at one ex- 115 treme side, the same being formed integral therewith and being given a longitudinal curve, the convex side of which is arranged to run in coöperation with the bottom of the ledger-blade and the free end of which 120 is downwardly bent so far as to prevent it from contacting under any circumstance with the bottom of either the filling-plate or the ledger-blade. It is the object of this 125 pilot to engage the bottom of the ledger-blade at the proper time in its rotation and prevent the ledger-blade and edge of the cutting-blade from contacting or injuring each other, and to compel the said ledger-blade and cutter-blade to coöperate with a 130

perfect shearing action as said cutter-blade is passing under and in contact with the ledger-blade. Primarily, the outer-blade can be adjusted on its carrier, by screws 82, 5 so as to place the same in substantially the correct coöperative relation with the ledger-blade and, after this first adjustment has been made, or if at any time the proper adjustment should be lost, the cutter-blade 10 can be adjusted into proper coöperative relation with the ledger-blade by simply manipulating the two adjusting-screws 79, coöperating with the short end 80 of the supporting-lever. The rotary cutter operates in the space between the two feed-bars and below the slot between the two throat-plates, and directly under the filling-plate and ledger-blade, and, consequently, 15 between the two feed-dogs, this making a simple and compact arrangement producing a perfect balance of the mechanisms and accurate handling of the work, since the latter is engaged by the yielding feet and the positively actuated feed-dogs on opposite 20 sides of the point or line of penetration of the thread-deflecting blade and engaged with equal pressure all around said point of penetration, thus avoiding any possibility of distorting or dragging the work; and 25 30 when the rotary cutter coöperates with its ledger-blade, it engages the dangling threads which have been deflected or drawn downwardly by the blade, so that, if the cutter should become dulled in operation, 35 the drag on the work would be against an equal pressure all around the cutting point or point of coöperation of the two blades. The disposition of the parts shown is also such that there is a perfect feeding coöperation 40 between the presser-feet and the feed-dogs resulting in feeding the work properly in a perfectly straight line across the work-plate, thus maintaining a straight line of 45 thread-drawing during the operation of the machine without the aid of guides or other auxiliary devices, and rendering it easy and simple for the most inexperienced operative to handle the fabric and present it to the machine for the thread-drawing operations. 50

From the foregoing detailed description, the mode of operation will be readily understood from the following: Motion being imparted in any suitable way to the 55 driving-shaft through the medium of the pulley, the blade-bar 6 is caused to vertically reciprocate. The fabric having been placed on the work-plate in proper position under the presser-foot and the latter lowered into 60 clamping contact, the feeding mechanism will operate in the usual manner to feed the fabric from front to rear or transversely of the machine during the reciprocations of the blade. The blade-point will penetrate

the work and, as it descends, its teeth or 65 points will catch the warp or weft threads, as the case may be, and the latter will be carried into the crotch of each tooth of the blade and then downwardly deflected and drawn through the work. The blade then 70 ascends and, as it leaves the cloth-plate, the rotary cutter sweeps around and engages the dangling threads extending between its cutting-edge and the edge of the ledger-blade and cuts the same off close to the bottom 75 surface of the work with a smooth shearing action. The feed then takes place by the dogs rising through the slots in the throat-plates and clamping the work against the bottom of the presser-feet, and then 80 moving forward, carrying the work with them for the adjusted distance, whereupon said dogs will descend below the throat-plates followed by the presser-feet, which will clamp the work firmly against the solid 85 parts of the throat-plate surrounding the point of penetration of the drawing-blade, the said feed-dogs then moving toward the front of the machine preparatory to rising again for their gripping and feeding action. 90

Having thus described my invention, what I claim and desire to secure by Letters Patent is:

1. A thread-drawing machine having, in combination, thread-deflecting means; and 95 feeding and presser-foot mechanisms coöperating to advance the work to and from the deflecting means; the presser-foot mechanism comprising a plurality of independent, substantially L-shaped, movable feet 100 disposed so as to produce a centrally-located opening, and to substantially inclose the area, within which the deflecting means operates, whereby the fabric is held firmly against stress of said deflecting means; and 105 means for severing the deflected threads.

2. A thread-drawing machine having, in combination, thread-deflecting means; feeding and presser-foot mechanisms coöperating to advance the work to and from the 110 deflecting means; the presser-foot mechanism comprising a bar having a shank provided with parallel arms, a foot mounted on each arm so as to have vertical movement thereon, and a spring interposed between 115 each of said feet and its supporting-arm to yieldingly depress the same into engagement with the work; and means for severing the deflected threads.

3. In a machine of the class described, and 120 in combination, means for deflecting the threads from the body of the fabric; means for feeding the fabric; a presser-foot having a plurality of independently movable members of substantially L-shape arranged in 125 overlapped or interlocked relation so as to substantially inclose the area of operation of the thread-deflecting means and prevent

movement of the fabric; and means for severing the deflected threads.

4. In a machine of the class described, and in combination, a ledger-blade; a filling-plate opposed to said ledger-blade and forming therewith an open throat; thread-deflecting means operating in said throat; means for feeding the fabric; a presser-foot; and means coöperating with said ledger-blade to sever the deflected threads.

5. In a machine of the class described, and in combination, means for deflecting the threads from the body of the fabric; means for feeding the fabric; a ledger-blade; a filling-plate opposed to said ledger-blade and providing a throat for the thread-deflecting means between the two; means for securing a relative adjustment between said ledger-blade and said filling-plate; a presser-foot; and means coöperating with said ledger-blade to sever the deflected threads.

6. In a machine of the class described, and in combination, means for deflecting the threads from the body of the fabric; means for feeding the fabric; a ledger-blade; a filling-plate; means for adjusting said ledger-blade; means for adjusting said filling-plate to form a throat for the thread-deflecting means between the two; a presser-foot; and rotary means coöperating with said ledger-blade to sever the deflected threads.

7. In a machine of the class described, and in combination, throat-plates having feed-dog openings therein; feed-dogs operating through said throat-plate openings; a ledger-blade and a filling-plate transversely adjustable with respect to said throat-plates to form a throat therebetween; means for adjusting said ledger-blade and said filling-plate relatively to each other; means for deflecting the threads from the body of the fabric through said throat; a presser-foot to hold the fabric; and rotary means beneath said ledger-blade and coöperating therewith to sever the deflected threads.

8. A thread-drawing machine having, in combination, a vertically-reciprocating thread-deflecting device; a feeding mechanism; a presser-foot mechanism; a divided throat-plate having slots through which the feed-dogs of the feeding mechanism operate; a filling-plate and a ledger-blade arranged in alinement in the space between the two parts of the throat-plate; means whereby the filling-plate and ledger-blade may be longitudinally adjusted to regulate the space through which the thread-deflecting blade operates; a cutter coöperating with said ledger-blade; and means for actuating the cutter.

9. In a thread-drawing machine, and in combination, thread-deflecting means; fab-

ric-feeding and presser-foot mechanism co-operating to advance the work; thread-cutting mechanism embodying a rotary cutter; and means for adjusting said cutter diametrically with respect to its axis of rotation.

10. In a thread-drawing machine, and in combination, thread-deflecting means; fabric-feeding and presser-foot mechanism co-operating to advance the work; thread-cutting mechanism embodying a rotary cutter; and means for adjusting said cutter to and from its axis of rotation.

11. A thread-drawing machine having, in combination, thread-deflecting means; feeding and presser-foot mechanism coöperating to advance the work relatively to the deflecting means; thread-cutting mechanism comprising a rotary thread-cutter; and a pilot carried by said cutter for maintaining it in its proper operative path.

12. A thread-drawing machine having, in combination, thread-deflecting means; feeding and presser-foot mechanism coöperating to advance the work relatively to the deflecting means; thread-cutting mechanism comprising a rotary thread-cutter; a ledger-blade coöperating therewith; and a curved extension carried at the forward end of said thread-cutter for coöperating with said ledger-blade to compel the proper coöperative action of the two.

13. A thread-drawing machine having, in combination, thread-deflecting means; feeding and presser-foot mechanism coöperating to advance the work relatively to the deflecting means; thread-cutting mechanism comprising a rotary thread-cutter; a ledger-blade coöperating therewith; and means for adjusting said ledger-blade relatively to the path of movement of said cutter.

14. In a machine of the class described, and in combination, means for deflecting threads from the body of the fabric; means for feeding the fabric; suitable presser-foot mechanism coöperating with said feeding means; a rotary cutter to sever the deflected threads; and means for adjusting said cutter angularly.

15. In a machine of the class described, and in combination, means for deflecting threads from the body of the fabric; means for feeding the fabric; suitable presser-foot mechanism coöperating with said feeding means; a rotary cutter to sever the deflected threads; a pivotal support for said rotary cutter; and means for adjusting said cutter angularly about said support.

16. In a machine of the class described, and in combination, means for deflecting threads from the body of the fabric; means for feeding the fabric; suitable presser-foot mechanism coöperating with said feeding means; and a rotary cutter to sever said de-

flected threads, said cutter comprising a rotary carrier, a blade-support pivotally mounted on said carrier, and means for adjusting said blade-support angularly about 5 its pivotal support.

17. In a machine of the class described, and in combination, means for deflecting threads from the body of the fabric; means for feeding the fabric; suitable presser-foot 10 mechanism coöperating with said feeding means; and a rotary cutter to sever the deflected threads comprising a rotary carrier, a blade-support pivotally mounted on said carrier, and a pair of adjustable screws to 15 hold the said blade-support in a predetermined position and provide for its angular adjustment.

18. In a machine of the class described, and in combination, means for deflecting 20 threads from the body of the fabric; means for feeding the fabric; suitable presser-foot mechanism coöperating with said feeding means; a rotary cutter to sever the deflected threads comprising a rotary carrier, a blade- 25 support pivotally mounted on said carrier, and a pair of adjustable screws to hold said blade-support in a predetermined position and provide for its angular adjustment; and a blade adjustable on said support.

30 19. A thread-drawing machine having, in combination, thread-deflecting means; feeding and presser-foot mechanism coöperating to advance the work relatively to the deflecting means; thread-cutting mechanism 35 comprising a rotary thread-cutter; a carrier therefor, and means engaging the carrier for controlling its initial operative position.

20. In combination with mechanism for deflecting threads of the body fabric, a cut-

ting mechanism for cutting the deflected 40 threads, a feeding mechanism for advancing the work to the deflecting mechanism, and a presser-foot mechanism for holding the work against the drag of the thread-deflecting mechanism, said presser-foot mechanism 45 comprising a yieldingly-depressed bar having independent means for yieldingly engaging the work around the path of movement of the thread-deflecting mechanism.

21. In combination mechanism for removing body threads from fabric to produce drawn work, including a thread-deflecting blade; feeding mechanism comprising a plurality of feed-dogs operating upon the work about the thread-deflecting blade; and means 50 coöperating with the work for creating a certain pressure upon the latter around the thread-deflecting blade and between the feed-dogs, so as to hold the work against the thrust of the blade in its thread-deflecting 55 movement.

22. A thread-drawing machine having, in combination, thread-deflecting means, feeding and presser-foot mechanisms coöperating to advance the work relatively to the 60 deflecting means, thread-cutting mechanism comprising a thread-cutter, a ledger-blade coöperating therewith, and means for adjusting said ledger-blade relatively to the path of movement of said cutter. 70

In testimony whereof I have hereunto signed my name in the presence of two subscribing witnesses.
